INVENTOR

UNITED STATES PATENT OFFICE.

RUDOLPH Z. NOLAN, OF ALTON, ILLINOIS.

WINDOW-SHADE ROLLER.

SPECIFICATION forming part of Letters Patent No. 752,096, dated February 16, 1904.

Application filed June 24, 1903. Serial No. 162,946. (No model.)

To all whom it may concern:

Be it known that I, RUDOLPH Z. NOLAN, a citizen of the United States, residing at Alton, in the county of Madison and State of Illinois, have invented new and useful Improvements in Window-Shade Rollers, of which the following is a specification.

My invention has relation to new and useful improvements in window-shade rollers of that type which include in their structure a spring for rotating the roller to wind the shade thereon and a pawl-and-ratchet device for holding the roller against return movement when the curtain is lowered.

The object of the invention is to provide a device of the character mentioned which is simple in construction and durable and efficient in use and which will embody in its structure an improved pawl-and-ratchet device.

The invention consists in providing one end of the roller with a ratchet-disk which is rigidly attached to and turns with the roller when the shade is raised and lowered and in mounting upon the roller-spindle a locking member through which the disk turns and in which is located a ball which by gravity engages the disk to prevent rotation of the roller.

I have fully illustrated my invention in the accompanying drawings, forming a part of this specification, wherein—

Figure 1 is a perspective view of one end of shade-roller, showing my invention applied in operative position thereon. Fig. 2 is an end view of my improved roller, the tubular casing being shown in longitudinal section and the ratchet-disk in end elevation. Fig. 3 is a longitudinal section through the end of the roller and my invention as applied thereto. Fig. 4 is a sectional view on the line 4-4 of Fig. 2.

Referring to the drawings, 1 designates a hollow shade-roller within which is arranged a spring (not shown) which is adapted to turn the roller in one direction for the purpose of winding the shade thereon in a well-known manner. Secured upon the end of the roller is a socket or cap-piece 2, having a closed end formed with a central circular opening 3, through which the spindle 4 extends, said spin-

dle being secured at its inner end to the spring 50 for actuating the roller and its outer end being squared, as at 5, for the purpose of insertion in any well-known form of shade-bracket, whereby the spindle will be held against movement when the roller is rotated in either direction. 55

Surrounding the opening 4 and projecting at right angles to the face of the socket or cap-piece is a cylindrical extension or neck 6, the end of which terminates a short distance beyond the cap-piece and is formed or provided with a disk 7, which is formed upon its periphery with a plurality of projections 8, the rear sides of which are curved, as at 9, the front portions being curved inwardly, as at 10, 65 to provide pockets or recesses for the purpose hereinafter specified.

11 designates a locking member which is rigidly mounted upon the spindle 4 and is secured thereon in an inclined position, as shown 70 in Fig. 1, by forming it with a longitudinally-extending central aperture through which the spindle 4 is projected. This locking member 11 is provided with a longitudinally-extending slot 12, within which the ratchet-disk 7 is 75 located and turns when the roller is rotated, said member being cut away at one side, as at 13, to provide for the free rotation of the cylindrical extension 6. At its upper portion this locking member 11 is hollowed out to provide a longitudinally-extending channel or raceway 14, in which is located a ball 15, which is of such a diameter as to travel easily within the raceway, but too large to permit of its being displaced through the slot 12, as shown in 80 Fig. 3. This ball is adapted by its own weight to fall into recesses 10 in the ratchet-disk in order to prevent the rotation of the roller 1 to wind the shade thereon.

It will be seen that the position of the disk 90 and locking member in operative relation is insured under all conditions in view of the fact that the locking member is rigidly mounted on the spindle 4 and that the body thereof adjacent the cut-away portion 13 extends well 95 within the periphery of the disk, whereby lateral and longitudinal displacement of the disk is prevented.

To provide for the insertion of the ball into its position in the locking member, the upper end of said member is provided with an opening 16, through which the ball is inserted, 5 the opening being afterward sealed by means of a plug of solder or in any other desired manner.

The operation of the invention is as follows: When the shade is pulled down, the disk 7 10 will be rotated in a direction such that the ball 15 will ride over the curved portions 9 of the ratchet-disk and will thereby be forced up into the raceway, the free rotation of the roller in the direction to lower the shade being unimpeded. 15 As soon as the shade is lowered to the desired point the ball 15 will roll down the raceway into one of the recesses 10, whereby the rotation of the roller in the opposite direction to wind the shade up will be 20 prevented. To raise the shade, it is pulled downwardly, so as to rotate the roller a short distance, which will serve to force the ball out of engagement with the disk up into the raceway. The spring within the roller will 25 then exert its force to rotate the roller in the opposite direction, the ball being thrown out of engagement therewith during the rotation of the disk. When the rotation of the 30 roller is stopped, the ball will then roll into

engagement with the disk and further rotation of the roller prevented.

It will be seen that I have provided a pawl-and-ratchet device which is extremely simple in construction and which will efficiently attain the objects for which it is devised.

Having thus fully described the invention, what is claimed as new is—

1. The combination with a shade-roller and its spindle, of a cap-piece provided with a ratchet-disk, having a central aperture through which the spindle extends, a locking member on the spindle, formed with a slot within which the disk rotates and means to engage the disk to prevent its rotation.

2. The combination with a shade-roller and its spindle, of a cap-piece provided with a ratchet-disk having a central aperture through which the spindle extends, a locking member on the spindle formed with a slot within which the disk rotates, a raceway in the locking member and a ball in the raceway adapted to engage the ratchet-disk to prevent rotation of the roller.

In testimony whereof I affix my signature in presence of two witnesses.

RUDOLPH Z. NOLAN.
